UNITED STATES PATENT OFFICE.

EDGAR H. MUMFORD, DECEASED, LATE OF PLAINFIELD, NEW JERSEY, BY ROSE S. MUMFORD, EXECUTRIX, OF PLAINFIELD, NEW JERSEY.

JOLT RAMMING-MACHINE.

1,171,869.

Specification of Letters Patent.

Patented Feb. 15, 1916.

Application filed June 17, 1915. Serial No. 34,710.

To all whom it may concern:

Be it known that EDGAR H. MUMFORD, late a citizen of the United States, residing at Plainfield, in the county of Union and 5 State of New Jersey, did invent certain new and useful Improvements in Jolt Ramming-Machines, of which the following is a specification.

This invention has reference to machines 10 for ramming sand molds and particularly to that type of machine known as a jolt rammer in which the moving parts are operated by fluid pressure, the supply of pressure being controlled by automatic valve mechanism. One of the chief objects of this invention is to provide a novel and improved 15 form of fluid pressure control valve mechanism which will operate efficiently and accurately.

20 The foregoing, together with such other objects as may hereinafter appear or are incident to the invention are attained by means of a construction illustrated in preferred form in the accompanying drawings, 25 wherein—

Figure 1 is a longitudinal section through a portion of a combined squeeze and jolt ramming molding machine such as shown in copending application of Edgar H. Mumford, Ser. No. 19,931, filed April 8, 1915; 30 Fig. 2 is a section similar to that of Fig. 1 showing a modification of the improvement; and Fig. 3 is a sectional view of another detailed modification of the improvement.

35 Improvements have been made in jolt ramming apparatus whereby the provision of mechanical means for positively shifting the valve controlling the supply of fluid pressure to the moving parts has been dispensed with, the control of the supply of fluid pressure being had through the medium of fluid pressure actuated valve mechanism. The invention relates more particularly to an improvement in this latter form 45 of mechanism.

For convenience of illustration, the invention is shown as applied to a combined squeeze and jolt ramming molding machine. Only such parts of the apparatus are shown 50 as are necessary to bring out the operation of the improvement. Referring now to Fig. 1, the apparatus comprises a main casting or base 7 which is provided with an annular upstanding cylindrical portion 8 and

55 with a centrally disposed cylindrical guide post 9. The mold table supporting frame is carried on the plunger 11 mounted in the cylindrical portion 8 of the base. The plunger 11 is hollow and is provided with a centrally disposed cylindrical portion 11^a 60 which surrounds and is guided by the central guide post 9. The squeezing operations of the machine are carried on by the introduction of fluid pressure into the cylinder 8 beneath the lower face of the plunger 11, 65 but as this forms no part of this invention, further description will be dispensed with.

Referring now to the mechanism for carrying out the jolt ramming operations, it 70 will be noted that there is a space in the cylinder 11^a above the post 9 to provide a valve chamber 12, and that a valve block 13 is detachably secured by means of the studs 14 to the top of the post 9. The valve block 75 is provided with a passageway for conducting fluid pressure to the interior of the cylinder 11^a, such passageway being comprised of a horizontally extending inlet passage 15, a horizontally disposed discharge passage 16 separated horizontally by the wall 17, 80 and the passage 18 in the wall 17 which serves to connect the passages 15 and 16. A vertically movable piston valve A controls the opening 18, such valve being provided 85 with an upwardly projecting stem 19 which is of such length that it projects slightly above the top face of the valve block 13 when the valve is in lower or open position. The lower face of the piston portion 20 of the valve is spaced away from the upper 90 face of the post 9, for a purpose which will hereinafter appear.

The post 9 has a central chamber 21, from 95 the upper portion of which an inlet port 22 extends to the upper face of the post opening at a point communicating with the downwardly extending end of the passage 15. Fluid pressure is introduced into the chamber 21 through an inlet pipe 23, the supply of fluid pressure being controlled by 100 any suitable form of valve mechanism (not shown) in the usual manner. An exhaust port or opening 24 is drilled in the wall of the cylinder 11^a, and the valve block at one end is spaced away from the inner wall of 105 the cylinder 11^a to form a space 25 with which the port 24 comes into register, as will further appear. A restricted passage

15^a extends from the end of the passage 15 to the space beneath the lower face of the piston portion 20 of the valve A.

The operation of the apparatus is as follows, assuming that the parts are in the position shown in Fig. 1: Fluid pressure is introduced into the chamber 21 through the supply pipe 23 and passes through the inlet port 22 into the passageway 15, thence through the opening 18 around the valve stem 19 into the discharge passage 16, and thence into the chamber 12, causing the cylinder 11^a and the plunger 11 of which the cylinder forms a part, to rise, carrying the frame 10 upwardly. During this period of operation, the pressures on the opposite faces of the lower portion of the valve A are substantially equalized as it will be seen that the passage 15^a permits an accumulation of pressure on the lower face of the piston 20 of the valve. However, the pressure on the upper face of the stem 19 of the valve tends to hold the valve off its seat. The parts continue their upward movement until the exhaust port 24 in the wall of the cylinder 11^a comes into register with the space 25, at which time the pressure in the chamber 12 exhausts through the port 24, thereby causing a rapid reduction of pressure above the valve. The passage 16 is covered by the rising wall of the cylinder 11^a just prior to the uncovering of the port 24.

The pressure accumulated beneath and acting against the lower face of the piston portion 20 of the valve then immediately causes the valve to move upwardly to close the valve opening 18, thereby cutting off the supply of fluid pressure from the chamber 21. The plunger 11 and cylinder 11^a fall, impacting on the upper face of the base 7. As the parts move downwardly, a tappet 19^a in the end of the cylinder 11^a comes into contact with the upper end of the stem 19 of the valve and moves the valve to open position, after which the operation above described is repeated, and the ramming of the mold effected.

Some difficulty has been encountered in preventing the valve from prematurely moving upwardly to close the opening 18, which obviously would result in an impairment of the efficiency of the device. To overcome this difficulty, the passageway 15 is formed so as to set up a peculiar swirling motion in the air as it flows therethrough, which causes the air to act against the valve to hold it in lower or open position. To impart this swirling motion to the air, the annular wall of the passageway 15 is rounded as indicated at 26. It is difficult to define accurately just what effect the rounding of the wall of the passageway 15 has on the air passing through the passageway, but it has been found by experience that the effect of so rounding the wall adjacent to the valve

is that the valve will remain in open or lower position until the pressure has been reduced in the chamber 12. The movement imparted to the ascending current of air causes it to impinge upon the upper faces of the valve parts in a downward direction, which offsets the tendency of the current passing through the opening 18 to draw the valve upwardly. This peculiar action of the currents of air may be perhaps best gathered from inspection of Fig. 3. In the construction therein shown, the rounding of the passageway 15 is accentuated by providing a downwardly-turned lip 27 on the wall 17 adjacent to the opening 18. The piston portion 20 of the valve in this type has a loose fit and pressure accumulates beneath the valve by leakage. The valve is introduced into the valve block from beneath, the plate 28 being thereafter detachably secured in place.

In Fig. 2 there is shown a slightly modified form of construction which differentiates from that shown in Fig. 1 in the manner in which the fluid pressure is conducted to the lower face of the valve. In this form of apparatus, the port 28 is drilled through the wall of the post 9 so as to communicate with the chamber 21, and a second port 29 located above the port 28 extends in an upward direction from a point above the port 28 opening into the space beneath the lower face of the valve parts. Mounted in the wall of the cylinder 11^a is a spring-held member 30 having a groove 31 in its inner face, which groove serves to connect the ends of the ports 28 and 29 after the cylinder 11^a has moved upwardly a predetermined distance. When these parts are brought into register, pressure flows from the chamber 21 through the port 28, groove 31 and port 29 to the lower face of the valve, the parts being so arranged that they are brought into register substantially simultaneously with the uncovering of the exhaust port 24.

It will be seen from the foregoing that the valve operates with great accuracy, which results in an increase in efficiency. Furthermore, the arrangement of the valve mechanism above the post 9 simplifies the whole structure as it obviates the necessity of forming special openings or recesses for the introduction of the valve parts, and special ports which otherwise might be necessary. The location of the valve parts above the post also gives added efficiency because the valve parts, by reason of their location, are immediately subjected to the effects of changes in pressure conditions.

I claim:—

1. The combination in a jolt ramming machine of a plunger member and a cylindrical member, relatively movable and provided with a fluid pressure chamber therebetween, one of said members being provided with

- an exhaust port, an admission port for introducing fluid pressure to said chamber, a valve casing in said chamber, and a valve in said casing for controlling said admission port, said valve being fluid pressure held in open position and being governed as to its closing movement by the said exhaust port when the latter is in registry with the said chamber.
2. The combination in a jolt ramming machine of a stationary plunger, a vertically movable cylinder mounted thereon, there being a fluid pressure chamber in the cylinder above the plunger and an exhaust port in the wall of the cylinder and an admission port in the plunger, a valve block mounted on the plunger and lying in said chamber and provided with a passageway in communication with said admission port, and a fluid pressure actuated valve in said block for controlling said passageway normally in open position and governed as to its closing movement when the exhaust port is brought into registry with the said chamber.
3. The combination in a jolt ramming machine of a stationary plunger, a vertically movable cylinder mounted thereon, there being a fluid pressure chamber in the cylinder above the plunger and an exhaust port in the wall of the cylinder and an admission port in the plunger, a valve block mounted on the plunger and lying in said chamber and provided with a passageway in communication with said admission port, and a fluid pressure actuated valve in said block for controlling said passageway normally in open position and governed as to its closing movement when the exhaust port is brought into registry with the said chamber, the wall of said passageway being rounded to direct the incoming current of fluid pressure downwardly against the valve.
4. The combination in a jolt ramming machine of a stationary plunger, a vertically
- movable cylinder mounted thereon, there being a fluid pressure chamber in the cylinder above the plunger and an exhaust port in the wall of the cylinder and an admission port in the plunger, a valve block detachably fastened to the top of the plunger and lying in said chamber and provided with a passageway in communication with said admission port, and a fluid pressure actuated valve in said block for controlling said passageway normally in open position and governed as to its closing movement when the exhaust port is brought into registry with the said chamber.
5. The combination in a jolt ramming machine of a cylinder member and a plunger member relatively movable, means for admitting fluid pressure into the cylinder member to raise the plunger member comprising a passageway, and a fluid actuated valve controlling said passageway, the wall of said passageway being formed to direct the incoming current of fluid pressure against a face of the valve to hold it in open position.
6. The combination in a jolt ramming machine of a cylinder member and a plunger member relatively movable, one of said members being provided with an exhaust port, means for admitting fluid pressure into the cylinder member to raise the plunger member comprising a passageway, and a fluid actuated valve controlling said passageway and open when in lower position, the wall of said passageway being formed to direct the incoming current of fluid pressure against a face of the valve to hold it in open position and the valve being governed as to its closing movement by the uncovering of said exhaust port.

In testimony whereof I have hereunto signed my name.
